UNITED STATES PATENT OFFICE.

CHARLES H. LOEW, OF LAKWOOD, OHIO.

PASTEURIZER.

No. 806,354.

Specification of Letters Patent.

Patented Dec. 5, 1905.

Application filed November 30, 1903. Serial No. 183,109.

To all whom it may concern:

Be it known that I, CHARLES H. LOEW, a citizen of the United States, and a resident of Lakewood, in the county of Cuyahoga and State of Ohio, have invented certain new and useful Improvements in Pasteurizers, of which the following is a specification.

My invention relates to pasteurizers for beer and similar liquids.

10 In pasteurizers of the type in which the liquids to be treated are while in packages slowly moved through a heated bath it has been found in practice that the changes of temperature upon going into and coming out 15 of the apparatus are apt to be so abrupt as to crack the packages containing the liquids if such packages are made of glass, which is commonly the case, and if an economical rate of movement is maintained by the conveyer.

20 In this type of apparatus the liquid-bath is commonly heated by steam forced into it under pressure, causing a large amount of steam to gather in the apparatus above the surface of the bath. If the steam is drawn 25 toward the inlet end of the apparatus by means of a chimney, it is apt to escape, leaving that part of the apparatus cold, so that when the bottles enter the hot bath they will crack. If, on the other hand, the steam is not 30 removed or prevented from reaching the inlet end, it accumulates at that place and is apt to be puffed out into the faces of the workmen engaged in loading the conveyer and scald them. At the outlet end another difficulty

The drawing is a central vertical section of the apparatus broken at the middle in order that the illustration may come within the limits of one sheet.

In the drawing, 1 is a long tank of iron 60 or other suitable material and provided with suitable inlet and outlet ports and with steam-pipes 2 or other means for heating its contents and adapted to be filled with water. At each end of the tank and adapted to revolve in suitable bearings are sprocket-wheels 3 3, arranged in pairs. Over these pass chains 4, supporting transversely between them slats or rods 5, the whole forming an endless flexible conveyer adapted 65 to carry through the bath the beer-bottles placed in cases. At the inlet end is mounted a third pair of sprocket-wheels 7, over which the conveyer also passes. The conveyer rises 70 inwardly at the inlet end to one end of a 75 guide 8. It rides down this guide into the bath, thence passes through the latter, and then up and out of it, emerging at the opposite end of the tank. The conveyer is propelled from a suitable source of power. (Not 80 shown.)

Above the tank and over the entire apparatus is a long cover 10, terminating at the inlet end in a hood 11 and at the outlet end in a similar hood 12. The respective walls 85 13 and 14 of these hoods depend vertically from the edges thereof and are provided with ports 15 and 16, through which the bottle-containing boxes are passed.

22. A pasteurizing apparatus comprising a tank having a pasteurizing portion between its ends and provided at one end with a preliminary heating chamber leading to said pasteurizing portion and its other end with a cooling-chamber leading from said pasteurizing portion; said chambers having steam or vapor containing portions through which are carried the articles being pasteurized, means in said preliminary-heating chamber acting in conjunction with the steam or vapor to produce a gradual increase in the heat applied in said chamber from its inlet to its outlet, and means in the cooling-chamber operating to produce an increasing cooling effect from the inlet to the outlet of said chamber.
- 15 23. A pasteurizing apparatus comprising a tank adapted to contain a heated liquid and provided at one end with a hood for steam or vapors, said hood having a part arranged beyond the end of said tank and provided with a plurality of devices for condensing the steam, a portion of said devices being arranged over the liquid in said tank and a portion thereof being arranged in the part of the hood which is beyond the end of said tank.
- 20 Witness my hand this 28th day of November, 1903, at the city of New York, in the county and State of New York.
- 25 CHARLES H. LOEW.
